WASHBOARD-TENSIONING DEVICE

Application filed August 21, 1928. Serial No. 301,092.

Our invention relates to tensioning devices for use in textile machinery, and more particularly to what is generally designated in the trade as wash-board tensioning devices.

5 With the wash-board tensioning device now in use much annoyance is experienced by the breaking of the thread when the machine starts after having been stopped.

Broadly speaking, the object of the present invention is to overcome this difficulty, so that the thread will not be broken when the machine starts.

Other advantages, such as greater durability, economy, etc., will appear in the subjoined description.

A leading feature of the invention consists in forming a device of this character with an internal recess or open space between its ends in the path traversed by the thread; 20 and a device of this character in which one or both of the mating pieces may be formed in sections, if desired, and the sections preferably so arranged that each section contributes its appropriate part of the recess or opening just referred to, thus making the same a composite recess or opening common to all the sections.

The invention consists in certain novel features of construction and arrangement of parts, as will be hereinafter described and claimed, reference being had to the accompanying drawings, in which:—

Fig. 1 is a perspective view of one of the similar mating pieces of one form of our wash-board tensioning device.

Fig. 2 shows the same form of construction from a different angle, to bring out more clearly the central recess of our device which is a very important feature thereof.

Fig. 3 is a top plan view of a modification in which the device is formed in four pieces, preferably all of equal length, with the transverse ribs of the lower pieces left intact, 45 and with complementary openings formed in the meeting ends of the upper sections, whereby the ribs of the upper section are cut away at this opening.

Fig. 4 is a view showing the device formed in four parts similar to Fig. 3, but with the

central opening extending clear through both the upper and lower parts of the device.

Fig. 5 is a sectional view showing the lower part of the device formed in a single piece, and the upper part formed in two pieces of equal length, with the ribs of both the upper and lower sections cut away at the centre of the device to form the central recess; and, Fig. 6 is a perspective view on a somewhat enlarged scale, of a form of the device similar to that shown in Fig. 5, except that the lower part, as well as the upper, is divided into two equal parts.

Referring further to the drawings, the numeral 1^a indicates one of the similar mating pieces of one form of our device, as illustrated in Fig. 1, and the character 1^a indicates a mating piece of the same form of construction shown in a different perspective, in order to bring out more clearly the central recess 2.

In the different figures of the drawings, the upper and lower mating pieces are provided at their ends with the slight recesses 3 to hold the threads against lateral play.

In all the forms of the device, the sections have the transverse ribs 4 with the trough or valley spaces 5 between them, so arranged that when two mating sections are put together, the ribs of each section fit into the trough spaces of the other, in the usual way.

In the form of the device shown in Figs. 1, 2, 5 and 6 of the drawings, the central recess is a closed recess when the respective mating pieces are in operative relation to each other.

In Fig. 3, the recess is open on top; and in Fig. 4, both the bottom and the top of the recess are cut away, so as to form a hole at the centre of the device where all the sections meet.

In Fig. 5 we have shown the lower part of the tensioning device in one piece, with the upper or mating portion formed in two sections indicated by the numerals 6 and 7.

In Figs. 3, 4, and 6, we have shown the upper and lower parts of the device each formed in two sections, all the sections being preferably of the same length, and each section recessed or cut away at the point where they

all four meet, in a way to provide one central recess or cutaway portion.

For purposes of convenience and discrimination in reference we have indicated the composite recess in Fig. 3, by the numeral 8; the central opening in Fig. 4, by the numeral 9; the composite recess in Fig. 5, by the numeral 10; and that in Fig. 6, by the numeral 11.

In operation, the thread 12 (as indicated in Figs. 3 and 4) passes longitudinally through the tensioning device, the two mating pieces of which are held together in a suitable supporting frame on the machine with which they happen to be used. It is well known that a section of thread or yarn of any considerable length, when being unwound from a skein, or ball, or spool, has a practically uncontrollable tendency to sway back and forth laterally, as it is unwound at one end and wound up or taken up at the other end; and the faster the machinery is running, the worse will be this swaying back and forth of the thread, which is known in the trade as looping or ballooning.

One of the principal uses of these washboard tensioning devices is to prevent this looping and ballooning as far as possible, but due to irregularities in the thread, and in the twist, and in the disposition of the twist to travel in the thread when pressed between the two mating pieces of the tensioning device, and due to irregularities in different parts of the contacting surfaces of the tensioning devices, and perhaps for other reasons, the threads, if permitted to travel across a short vacant space between the mating pieces of the tensioning device, will tend to form a bend or loop in that space. When the machines are running fast, and then are stopped, the tendency of the twist in the thread to readjust itself will tend to make a loop in the thread where there is a section of it left free from pressure. Such a loop is indicated by 12^a in Figs. 3 and 4. When the machine stops, the portions of thread that are pressed between the two mating plates will have to remain about as they were, but in the free section of thread extending across the central opening 9 (Fig. 4), the twist in the thread (which twist is always disturbed while being run between two surfaces pressing on opposite sides of it) will equalize itself, and in the effort to do so will tend to make a bend in that section, as is the nature of twisted thread to do.

But the question naturally arises, as to what advantage comes from having the loop 12^a formed in the tensioning device; and that brings us to a consideration of the essential facts relative to the utility of the invention, which facts are as follows:—These washboard tensioning devices, as at present constructed and used, work admirably, but for one bad defect already referred to: just as

the machine starts up after having stopped, they break the thread with distressing frequency. When the machine is once started, then they work all right. If the tension is to be in danger of breaking in starting, that is not as much tension as is needed for the best made sufficiently light for the threads not to work after the machine is going; and thence the problem is to leave the tension as it is, and yet devise some method of eliminating the woeful frequency with which the device breaks the threads in starting.

With the present arrangement of washboard tensioning device, the thread is usually practically straight in the device, and is in frictional contact with all the ribs of both mating pieces of the device, so that in starting up the machinery, a strain is imposed on this thread sufficient to instantly overcome all that friction; and that is what breaks the thread.

Now, with our improved device, that unfavorable situation and outcome is remedied, for the thread has a loop 12^a at its centre, which loop portion is not in frictional contact with the ribs of the tensioning device (because the ribs at that point are cut away), and therefore, when the machine starts going, strain is imposed on the upper end of the thread down to that loop, and then the loop straightens before the further strain of starting the rest of the thread is imposed on the thread. That is to say; the part of the thread in the upper half of the tensioning device is already in motion before the part in the lower half of the device has offered any resistance to the forward movement of the thread. In this way the starting strain imposed on the thread, instead of being taken up all at once as by the old method, is taken up by our method in three installments, as follows:—first, the portion of thread in the upper part of the tensioning device; secondly, the loop 12^a which is next straightened out; and, thirdly, the portion of the thread in the lower part of the tensioning device.

In addition to the above, attention is called to one other fact, namely; that practically all twisted threads are more or less elastic, when left free and out of frictional contact with other bodies; and hence the loop 12^a being a free section of thread, of a material length, is somewhat elastic even when straightened, and therefore will render the thread less liable to break than if the central recess or opening of the device was wanting, as in the ordinary tensioning device.

In the next place, the fact that the mating pieces of our tensioning device are formed in sections, really provides, as it were, a loose joint at the middle of the device, which permits the separate parts of the device to yield, independently of each other, to the strain suddenly imposed upon the thread when the machine starts. It is a fact too well known

to need any elaboration, that a very slight yielding often saves a break; and therefore, the very fact that our device is formed of a plurality of pieces movable independently of each other, is a point of practical importance independently of the recess or opening at the centre.

Another point not to be overlooked is this, that experience has proved that these tensioning devices, in order to work to the best advantage, must be of considerable length in order to give the requisite amount of frictional resistance without too much pressure. This is found to be much better than a shorter tensioning device with the mating pieces more firmly pressed together. For this reason these tensioning devices have to be three or four inches long; and a piece of porcelain that long is very liable to break if it falls; and hence breakage runs high in the ordinary two-piece washboard tensioning device. But when one or both of the mating pieces is made in two sections, the liability of one of the short sections to break when it falls on the floor, is greatly diminished. But if it is broken, there is still only that one short piece to be replaced. Moreover, if one of the pieces gets worn and has to be replaced, it is only one little section that has to be replaced, instead of the whole upper or lower half of the device, as in the ordinary washboard tensioning device. Hence it will be seen that there is a considerable economy effected in our form of the device, apart from the fact that the forming of the device in a plurality of parts that will yield to the various strains imposed upon them, will of itself cause the device to wear longer than the old form of tensioning device.

Inasmuch as our device provides a certain degree of slackness in the thread instead of tautness, as in the old form, it insures a better product, due mainly to the fact that there is far less breakage of the yarn. This also helps to increase production.

In certain kinds of very fine work, it has been found impossible to operate with the ordinary washboard tension device, since there is practically no let-up on the tension when the machine is stopped, and therefore the thread remains taut. Hence, at the starting of the machine, the tension on the very fine strands of silk is so great that they break. This is entirely eliminated by the cut-out section in our device, which allows just enough slackness to insure easy starting. Therefore our new tensioning device has a wider range of work than the old devices, which fact is accentuated by the further consideration, that not only is our device suited to all kinds of work from the finest to the coarsest drawings of silk, but will also function perfectly under all other conditions such as dry and wet winding.

The uniqueness of our arrangement is fur-

ther accentuated by the fact that recent attempts to improve these tensioning devices show the provision of means apparently intended to hold the threads more taut even than formerly, if such were possible, whereas our device looks in exactly the opposite direction, and provides means for producing a certain amount of slackness in the thread—the very opposite of what has heretofore been attempted.

The great practical value of having slack in a thread is shown in a general way, in the operation of sewing machines, in which the thread, at each change in the direction of the movement of the needle is rendered slack at the start, with the result that a sewing machine can be run by electricity at an almost unbelievable rate of speed with little or no danger of breaking the finest thread.

In order to insure a perfect tension, the ordinary two-section tensioning device must be inserted in the holder in perfect alinement therewith, and that requires the services of a skilled mechanic. In addition to that, another very important consideration is that the back-faces of the sections must be absolutely level or even. But due to the excessive heat required in the baking of these ordinary washboard tensioning devices, the sections often become more or less warped or distorted in the baking, so that the uniform thinness and evenness of the sections is destroyed to such an extent that there are at times as high as 75% of defectives in a batch of the devices when they come out of the kiln or baking oven.

In considering this feature of the case, it must be borne in mind that the length of the sections must be maintained; and that this length, being very considerable, adds greatly to the tendency of the sections to warp in the baking.

It is manifest that so much waste in the final operation of manufacture makes the devices expensive. But in our now three or four piece device, the sections, due to their shortness, can be turned out more nearly perfect, as to straightness and freedom from warp, and hence are more easily held in perfect alinement; and at the same time the cost of production is greatly reduced.

From the foregoing it will be seen that we have produced a washboard tensioning device with greatly reduced liability to breakage; one that is durable and economical, and which, in the quality of its performance, marks a decided advance on the previous art.

Having now described the principles of our invention, and shown some of the ways in which its principles may be applied to actual use, what we claim as new, and desire to protect by Letters Patent is:—

1. A device of the character described, comprising upper and lower mating pieces for pressing the thread, the upper mating piece

being formed in sections, the device being provided with a cutaway portion in the path of the thread at the point where said sections meet, whereby to free a section of the thread from pressure.

5. 2. A device of the character described, comprising a plurality of upper and lower mating pieces, each of said pieces having a recess in the path of the thread at the point where 10 all of said pieces meet, all of said recesses being arranged to combine into one large composite recess located in the path of the thread, whereby one section of the thread has free passage as it crosses said recess.

15. 3. A device of the character described, comprising upper and lower mating plates formed in equal sections, said sections being recessed at the common meeting point of all of said sections, said recesses being arranged 20 to combine into one large recess located in the path of the thread as it traverses the device.

4. A device of the character described, comprising upper and lower mating pieces for exerting a clamping pressure on the 25 thread, the upper mating piece being formed in two equal sections, whereby to render said upper mating piece capable of slight yielding at its central portion.

5. A device of the character described, 30 comprising upper and lower mating pieces for exerting clamping pressure on the thread, with each of said pieces being formed in two equal sections, whereby to render the device yielding at its central portion.

35. 6. A device of the character described, comprising mating pieces for applying frictional pressure upon the threads passing therebetween, the device being divided midway between its ends, to render it flexible at 40 its centre; and being also provided with means for relieving the frictional pressure upon a section of the thread at said point of division.

7. A device of the character described, 45 comprising mating plates in face to face engagement with each other and arranged for the thread to pass between their meeting faces, said plates being provided between their ends on their respective contacting faces 50 in the path of the thread, with complementary cutaway portions uniting to form a single recess through which the thread passes without obstruction; whereby the section of thread progressively passing through said 55 recess is free to straighten itself and to play laterally in the recess.

8. A device of the character described, comprising mating plates in face to face engagement with each other and arranged for 60 the thread to pass between their meeting faces, said plates being provided between their ends on their respective contacting faces, in the path of the thread, with complementary cutaway portions uniting to form 65 a single recess through which the thread

passes without obstruction, said plates being provided on their meeting faces with transverse corrugations; said complementary recesses being formed by cutting away a plurality of adjacent corrugations in each plate at the point where the recess occurs; whereby to cause said recess to extend a material distance in the direction of the longitudinal extent of the thread.

9. A device as set forth in claim 7, the meeting faces of said mating plates being in continuous engagement with the whole portion of thread received therebetweeen except the section spanning said composite recess.

10. A device of the character described, comprising mating plates in face to face engagement with each other arranged for the thread to pass between their meeting faces, said plates being provided on their respective contacting faces, in the path of the thread, with complementary cutaway portions uniting to form a single recess through which the thread passes without obstruction; said plates being provided on their meeting faces with transverse corrugations; said complementary recesses being formed by cutting away a plurality of adjacent corrugations in each plate at the point where the recess occurs; whereby to cause said recess to extend a material distance in the direction of the longitudinal extent of the thread; said plates being provided with guide notches for the thread in the end corrugations of the plates, said recesses being located between said guide notches in alinement with them.

In testimony whereof we affix our signatures.
